HYGROMETER

Ralph A. Needham, Lone Rock, Wis.

Application May 24, 1937, Serial No. 144,505

5 Claims. (Cl. 73—337)

My invention relates to hygrometers and includes among its objects and advantages the provision of a novel device for measuring and registering the moisture content of the surrounding atmosphere.

In the accompanying drawing:

Fig. 1 is a perspective view of the front face of my invention;

Fig. 2 is a perspective view of the rear face;

Fig. 3 is a sectional view along the line 3—3 of Fig. 2;

Fig. 4 is a sectional view along the line 4—4 of Fig. 3;

Fig. 5 is a sectional view along the line 5—5 of Fig. 2;

Fig. 6 is a fragmentary detail view;

Fig. 7 is a sectional view along the line 7—7 of Fig. 3; and

Fig. 8 is a sectional view along the line 8—8 of Fig. 3.

In the embodiment selected to illustrate my invention I make use of a sheet of cardboard 10 of 8 or 10 ply thickness which may, for example, be 11 by 14 inches. The grain of the paper runs horizontally when viewing Figs. 1 and 2. In Fig. 1, I illustrate the sheet 10 as a support for the calendar 12, and the additional space may be utilized for advertising purposes.

Upon the rear face of the sheet 10 I mount an indicating needle 14. This needle includes a pointed end 16 exposed through a sight opening 18 and arranged in reading relation with the indicia 20 indicating atmospheric conditions in terms of moisture content. Referring to Fig. 8, the needle 14 is provided with an opening 22 fitting snugly but loosely upon a pin 24 which extends through an opening 26 in the sheet 10. A washer 28 is mounted on the pin 24 adjacent the front face of the sheet 10 while a spacing sleeve 30 is positioned between the needle 14 and the rear face of the sheet. The pin 24 includes a reduced shank 32 for the reception of a washer 34. The pin 24 is riveted at its ends, as indicated at 36, for connecting the parts in assembled relation. Sleeve 30 holds the needle in spaced relation with the rear face of the sheet 10 so as to permit free movement of the needle about the pin as an axis.

A wire 38 has one end hooked at 40 and passed through an opening 42 in the needle 14 in close relation with the pin 24. The opposite end of the wire 38 is bent to provide an eye 44 through which a bolt 46 extends. Bolt 46 passes through a slot 48 in the sheet 10 and includes a head 50 bearing against the front face of the sheet. A

nut 52 has threaded relation with the bolt for holding the eye 44 in assembled relation therewith. Slot 48 permits the bolt 46 to be adjusted longitudinally of the slot for making proper adjustment of the needle 14. Eye 44 may be clamped firmly against the rear face of the sheet 10 for holding the bolt 46 in its adjusted position.

A paper strip 54 is adhesively secured to spacing strips 56 adhesively secured to the rear face of the sheet 10. Strip 54 extends across the sight opening 18 in such spaced relation with the sheet 10 as to permit the needle 14 to pivot freely. Strip 54 affords protection for the needle to prevent accidental bending, as when handling and packaging, and holds the needle in spaced relation with the wall or other support for the sheet 10.

I prefer to make the strip 54 of the same material as the sheet 10 so as to have the same coefficient of expansion. The face of the strip 54 adjacent the sheet 10 may be white in color with the visible portion of the needle colored black to facilitate reading. Other contrasting colors may be employed and the color of the strip 54 may be the same as the visible face of the sheet 10.

To each of the vertical edges of the sheet 10 I connect a U-shaped metallic strip 58. The margins of the vertical edges are pinched lightly between the flanges of the strips, which strips operate to prevent curling of the sheet 10. While the strips 58 prevent buckling of the sheet 10, the sheet may expand and contract freely so as not to impair its reaction to variable moisture content. The pinching relation between the strips and the vertical edges of the sheet is merely sufficient to hold the strips in connected relation with the sheet, thus permitting free expansion and contraction.

An endless cord 60 passes through openings 62 in the sheet and may be hooked over a supporting pin 64.

In operation, the device reacts to the action of moisture on the paper sheet 10. Increased moisture content of the air causes the paper to lengthen while decreased moisture content will cause the paper to shrink and shorten. Such lengthening and shortening of the paper is indicated and amplified by the movement of the points 16 with respect to the indicia 20. The indicia may be in terms of percentages of moisture, as indicated in Fig. 1. Considerable amplification in the shifting action of the pointed ends 16 is attained because of the relation between the pivotal axis of the needle 14 and the wire 38.

A device according to my invention is sensitive to the slightest changes in moisture content in the air. The device may be manufactured at a relatively low cost and embodies a novel and accurate mechanism for registering relative humidity. The sheet 10 while constituting a part of the hygrometer provides a relatively large area for advertising purposes.

Without further elaboration, the foregoing will 10 so fully explain my invention that others may, by applying current knowledge, readily adapt the same for use under various conditions of service.

I claim:

1. A hygrometer comprising a sheet having 15 such properties as to lengthen or shorten in response to variations in the moisture content in the surrounding atmosphere, said sheet being provided with a sight opening and moisture indicating ratios on its front face, a needle located 20 on the rear face of the sheet and pivotally mounted thereon, said needle having a point exposed through said sight opening, said needle being pivotally connected near one end of the sheet, and a link having one end pivotally connected with the 25 needle and its other end attached to the sheet near the opposite end thereof.

2. A hygrometer comprising a sheet having such properties as to lengthen or shorten in response to variations in the moisture content in 30 the surrounding atmosphere, said sheet being provided with a sight opening and moisture indicating ratios on its front face, a needle located on the rear face of the sheet and pivotally mounted thereon, said needle having a point exposed 35 through said sight opening, said needle being pivotally connected near one end of the sheet, a link having one end pivotally connected with the needle and its other end attached to the sheet near the opposite end thereof, and a guard carried 40 by the rear face of the sheet for protecting the needle.

3. A hygrometer comprising a sheet having such properties as to lengthen or shorten in response to variations in the moisture content in 45 the surrounding atmosphere, said sheet being

provided with a sight opening and moisture indicating ratios on its front face, a needle located on the rear face of the sheet and pivotally mounted thereon, said needle having a point exposed through said sight opening, said needle being 5 pivotally connected near one end of the sheet, a link having one end pivotally connected with the needle and its other end attached to the sheet near the opposite end thereof, and means for adjusting the link, to permit the needle to be accurately adjusted with respect to said indicia.

4. A device of the type described comprising a sheet having such properties as to lengthen and shorten in response to moisture content of the surrounding atmosphere, an indicating needle 15 pivotally mounted on the sheet, moisture indicia on the sheet in operative relation with the needle, an operating connection between the sheet and the needle for imparting pivotal action to the latter in response to lengthening and shortening of 20 the sheet, metallic liners along two opposite edges of the sheet, said metallic liners being U-shaped in cross section and having pinching relation with the sheet, to prevent buckling thereof, but operating to permit free expansion and contraction of 25 the sheet.

5. A hygrometer comprising a sheet having such properties as to lengthen or shorten in response to variations in the moisture content in the surrounding atmosphere, said sheet being 30 provided with a sight opening and moisture indicating ratios on its front face, a needle located on the rear face of the sheet and pivotally mounted thereon, said needle having a point exposed through said sight opening, said needle being 35 pivotally connected near one end of the sheet, a link having one end pivotally connected with the needle and its other end attached to the sheet near the opposite end thereof, and a guard carried by the rear face of the sheet for protecting 40 the needle, said guard extending across the sight opening with the needle positioned between the guard and said sheet, said guard and the needle having contrasting colors.
